US00D450842B1

(12) **United States Design Patent** (10) Patent No.: **US D450,842 S**
Simon et al. (45) Date of Patent: **** Nov. 20, 2001**

(54) **DERMABRASION SYSTEM**

- (75) Inventors: **Eric M. Simon; Randall D. Block,**
both of Salt Lake City, UT (US)
- (73) Assignee: **Dynatronics Corporation**, Salt Lake
City, UT (US)
- (**) Term: **14 Years**
- (21) Appl. No.: **29/119,496**
- (22) Filed: **Feb. 28, 2000**
- (51) LOC (7) Cl. **24-02**
- (52) U.S. Cl. **D24/146**
- (58) Field of Search D24/133, 146,
D24/144; 606/131, 130, 159; 600/569,
562, 568

(57) **CLAIM**

The ornamental design for a dermabrasion system, as shown and described.

DESCRIPTION

FIG. 1 illustrates a perspective view of the dermabrasion system in accordance with the present invention; FIG. 2 illustrates a back perspective view opposite that of FIG. 1;

FIG. 3 illustrates a front plan view of the dermabrasion system of FIG. 1;

FIG. 4 illustrates a top plan view of the dermabrasion system of FIG. 1;

FIG. 5 illustrates a left side plan view of the dermabrasion system of FIG. 1;

FIG. 6 illustrates a right side plan view of the dermabrasion system of FIG. 1;

FIG. 7 illustrates a bottom plan view of the dermabrasion system with the cover panel removed of FIG. 1; and, FIG. 8 depicts a rear plan view of the dermabrasion system of FIG. 1.

The broken line showing of the power cord in FIG. 2 is for illustrative purposes only and forms no part of the claimed design.

1 Claim, 4 Drawing Sheets
